Henry L. Chemery.
ATTORNEY.

UNITED STATES PATENT OFFICE

GERALD P. CLIFFORD, OF FALMOUTH, MAINE

TOOTHBRUSH

Application filed April 26, 1930. Serial No. 447,667.

The invention hereinafter to be described relates to improvements in devices for cleaning the teeth and its object, stated in general terms, is to provide a tooth brush in the structure of which are incorporated certain features which when practical application is made of them renders the operation of tooth cleaning more thorough and satisfactory.

In properly cleaning one's teeth—which implies that all surfaces as well as the spaces between the teeth shall be gone over and acted on by the bristles of the brush, and remnants of food, film deposit and bacteria caused by decomposed matter be removed—

10 it is of the utmost importance that the shape of the brush be such that its bristles can conveniently reach every exposed surface of the teeth, starting from the gum margins.

It is a somewhat difficult matter, particularly with children, to manipulate the ordinary tooth brush to accomplish the above mentioned object due to the fact that the inner and outer surfaces of the molars and bicuspids, more particularly at the gum margins, together with the inner surfaces of the remaining teeth are especially inaccessible, and experience proves that these parts rarely receive the brushing required and for this reason are highly susceptible to the ravages of decay.

The object and advantage of my improved tooth brush resides primarily in its ability, when properly used, to reach and operate on these portions of a person's teeth just referred to, and which, when employing the conventional type of tooth brush are ordinarily deprived of proper care.

A conception which in its fundamental aspects would be in accord with the spirit and intent of my invention contemplates a tooth brush in which the bristles are arranged in the form of a T in plan view, the longitudinal and transverse bristle-carrying members being integral.

Taking cognizance, however, of the fact that a straight tooth brush is in certain instances desirable I construct my brush, in its preferred embodiment, so that to all intents and purposes it is a duplex affair, combining

in a unitary structure two distinct types of brushes.

In one form of brush included in my duplex arrangement the bristles are disposed substantially as they are in the ordinary tooth brush, that is, longitudinally of the handle, but in the other, through facilities provided to alter its form, the bristles are arranged in two banks, one disposed longitudinally of the handle and the other positioned transversely thereof, evolving in this latter type a brush with bristles arranged in substantially the shape of the letter T.

The actuating elements employed to change the form of the brush from straight to T shape, or vice versa, comprise a simple swiveling and locking mechanism and the operation to effect the change from one to the other type of brush requires but an instant of time and accomplished without resort to independent or outside means.

A further advantage occurring from the use of my improved brush, when the parts are arranged in the T form, is that while the transverse portion is operating on the sides of certain of the teeth—as for instance, the molars—its longitudinal part is simultaneously cleaning the crown surfaces of the adjacent teeth.

The character of my invention may best be understood by reference to the description found in the following specification when taken in connection with the accompanying drawing in which is disclosed, as an illustrative embodiment, one which, at the present time, I consider preferable to other possible forms in which the invention might be carried out.

In the drawings—

Fig. 1 and Fig. 2 represent, respectively, a perspective and inverted plan, in fragmentary views, of the simplest form of my T shape tooth brush;

Fig. 3 is a perspective of my duplex brush, showing it in its straight form;

Fig. 4 is the same as Fig. 3, except that the adjustable portion is shown swung at a right angle to bring the brush into T formation;

Fig. 5 is a fragmentary view of the bristle end of the brush, greatly enlarged, the slide being withdrawn from the square locking pin;

Fig. 6 is a longitudinal, central sectional elevation through the brush;

Fig. 7 is a transverse sectional elevation taken on line 7—7, Fig. 6;

Fig. 8 is the base plate, Fig. 9 the slide, and Fig. 10 the locking pin of the actuating parts of the brush, and

Fig. 11 shows one application of the tooth brush.

Similar characters are employed to identify like parts.

Figs. 1 and 2 of the drawings disclose the essence of my invention with respect to the disposition of the bristles which in plan view are arranged in T formation.

This brush, when its parts are disposed as seen in Figs. 1 and 4 is unique in that the bristles readily adapt themselves for tooth-cleaning service at practically any angle at which the brush is presented to the teeth.

The back teeth are usually cleaned by a succession of short forward and backward strokes of the brush combined with a slight rotary movement thereof, using, preferably, the form of brush shown in Fig. 4, whereas the front teeth, on their outer sides, may be cleaned by a combination of up and down and rotary movements of the tooth brush. And, although the T form is applicable and serviceable for operating on any and all of the teeth, a straight brush may for some individuals seem best suited and advantageous for cleaning certain surfaces of the teeth which are most accessible.

Therefore, and for the foregoing reasons, I have constructed my duplex brush so that in a unitary structure there are provided the elements with which to procure almost instantly either one of two different forms or types of tooth brushes, illustrated, respectively, in Figs. 3 and 4.

Fig. 4 shows one of the bristle-carrying portions swung at ninety degrees from the handle, converting the brush into one substantially of the same form, with relation to the bristles, as is illustrated in Fig. 1.

The structure by the use of which it is possible to make the change from one form of brush to the other comprises a base plate 1 secured to the portion 2 of the handle 3 by the screws 4. On the outer end of the base plate is a hole 5 through which operates the round part 6a of the locking pin 6.

Slidably mounted on the base plate is a slide 7 having on its outer end a squared recess 8 which upon the forward movement of the slide engages the square portion 6b of the pin 6. The adjustable portion 9, which, like the portion 2 carries bristles 10, has a square hole 11 in which the small, square end 6c of the pin 6 is fixed—the square construc-

tion keying the pin to the portion 9 and preventing relative movement therebetween.

The edges of the slide member 7 are turned inwardly enclosing the base plate and holding the slide against transverse displacement from off the plate. A thumb hold 7a is provided for actuating the slide, which latter when retracted allows the portion 9 to swing in either direction; and when aligned with the portion 2 or positioned at a right angle thereto, as seen in Figs. 3 and 4, respectively, the portion 9 may be locked against rotary movement with respect to the base plate by extending the slide member 7 so that the recess 8 engages the square part 6b of the pin 6.

The end of the portion 2 and both ends of the portion 9 are preferably arcuate in form, the former being concave and the latter convex. This is for the purpose of procuring a close joint between the parts when longitudinally aligned, as shown in Fig. 3.

In use, the tooth brush illustrated in Fig. 3 is useful in cleaning the outer surfaces of the front teeth and portions of the others whose surfaces are easiest of access.

In the Fig. 4 form its application covers a larger field as the laterally projecting portions of the member 9 permit of the bristles easily reaching the inner and outer surfaces of the molars and bicuspids, particularly at the gum margins, as well as the inner sides of the remaining teeth—these places being the most difficult to clean and therefore frequently neglected when employing the ordinary form of tooth brush.

Fig. 8 graphically illustrates the utility of my T form of brush, the bristles in the transverse portion reaching the inner sides of the teeth and gums while the longitudinal portion of the bristles operates on the crown surfaces of the adjacent teeth.

Modern dental technic dictates certain movements adapted to procure the best results in cleaning the teeth. They include up and down and crosswise movements combined with a slight rotary action of the brush, all of which movements may be employed in manipulating my brush.

In my duplex style of brush there are embodied features which I believe characterize it as a universal tooth-cleaning implement and which in practical use will be found to possess superior merit.

What I claim is:

1. A tooth brush comprising a handle, bristles extending from one of the faces of said handle, near one end thereof, a plate secured to and extending forwardly of the bristle-carrying portion of said handle, an aperture in the forward end of said plate, an auxiliary member having bristles thereon disposed beneath the apertured end of said plate, a pin fixed in said auxiliary member, adaptable of rotation in said aperture, and

means to lock said pin against rotation in said aperture.

2. A tooth brush comprising a handle, bristles extending from one face of said handle, near one end thereof, a plate secured to said handle and extending forwardly thereof, a pin-pivoting hole in the forward end of said plate, an auxiliary member, having bristles thereon, disposed beneath the forwardly extended portion of said plate, a pin journalled in said pin-pivoting hole and fixedly secured in said auxiliary member, a squared portion on said pin, a slide reciprocably mounted on said plate, a squared, open end socket on the forward end of said slide adapted, when said slide is advanced, to engage the squared portion on said pin and hold it against rotation in said plate, and a thumb-hold for the purpose of reciprocating said slide into and out of engagement with said pin.

3. A tooth brush comprising a main handle portion having near one end a bank of bristles extending outwardly from one face, an auxiliary bristle-carrying portion having the same width as and a greater length than the transverse measurement of the main handle bristle-carrying portion, means to pivotally attach said auxiliary portion to said main portion of the handle, and means adapted to lock the auxiliary bristle-carrying portion to the main bristle-carrying portion in, relatively, two different positions only, one in which the two portions are in longitudinal alignment and the other in which the auxiliary portion is transversely disposed on the end of the main portion, all bristles included in both sections of the handle pointing in the same direction regardless of the position of the auxiliary portion of the brush.

In testimony whereof I affix my signature.
GERALD P. CLIFFORD.
